UNITED STATES PATENT OFFICE.

WILLIAM T. DUNFORD, OF NEW YORK, N. Y., ASSIGNOR, BY DIRECT AND MESNE ASSIGNMENTS, TO SHURLOC ELEVATOR SAFETY CO., INC., A CORPORATION OF NEW YORK.

ELEVATOR-LOCK.

1,291,798.

Specification of Letters Patent. Patented Jan. 21, 1919.

Application filed January 7, 1914. Serial No. 810,737.

To all whom it may concern:

Be it known that I, WILLIAM T. DUNFORD, residing at 364 West 117th street, city, county, and State of New York, (and whose 5 post-office address is World Building, New York city,) have invented certain new and useful Improvements in Elevator-Locks, of which the following is a specification.

The object of this invention is to provide 10 means for positively insuring the locking of elevator shaft doors before the car can be started from the respective landings. This is accomplished by providing suitable mechanism on the car for rendering the controller inoperative, and by coöordinating this mechanism, that is by placing it in co-operative relation with a lock for each shaft door when the car is at the corresponding landing, thereby causing the controller to be 15 rendered inoperative by the act of unlocking the door and preserving this condition until the door is not only shut but relocked, the operation of relocking the door, reciprocally, causing or permitting the mechanism on the 20 car to return to normal condition, so as to render the controller operative again. Another object is to guard against failure, in the case of elevators operated by an electric motor, by causing the mechanism on the car 25 both to lock the controller and to break a circuit which controls the movement of the car. A further object is to provide a construction that is susceptible of embodiment in extremely simple form, more particularly 30 in respect to the devices installed at the several landings. Other objects and features of the invention will become apparent as the specification proceeds.

The accompanying drawings illustrate a 35 preferred embodiment of the invention, it being understood that numerous other specific constructions not illustrated may be devised for carrying the invention into effect. In these views:

Figure 1 is a perspective view of my elevator lock mechanism in place;

Fig. 2 is a plan view of the lock and its operating mechanism;

Fig. 3 is a detail view showing part of the 40 lock for the controller, partly in section;

Fig. 4 is a detail view of the connection between the lock rod and the rock shaft.

An elevator car is indicated at 10, and 45 11 is a door to the shaft at one of the landings.

The controller 12 in the car may be of any

suitable or approved character, and as will be understood, in elevators driven by electric power, has circuit-controlling provisions whereby the car may be started and stopped and run in either direction. 60

I also provide the car with mechanism, indicated generally by the reference character C, for rendering the controller inoperative. My invention is not necessarily limited to the specific character or mode of 65 operation of this mechanism, and naturally the selection of an appropriate train of parts is within the province of the skilled mechanic. The mechanism may render the controller inoperative by locking it in neutral 70 position, or by breaking or otherwise affecting the condition of a circuit, such that it would be impossible to start the car by the controller even if the latter could be moved. 75

I prefer, however, to do both. Briefly describing the specific car mechanism illustrated, 13 is a slide bar, appropriately mounted and guided beneath the floor of the car, 14 is a circuit-breaker having a projecting arm 15 in the path of a projection 16 on said bar, 17 is a rock-shaft, having an arm 18 engaged by the slide bar, and 19 is a locking rod pivoted to another arm 20 on said rock-shaft and extending upward through a guide tube 21 inside the casing of 80 the controller. The upper end of this rod is normally out of operative relation to a notched part 22 on the controller lever, but when the slide-bar is moved rearward the consequent working of the shaft raises the 85 locking rod into engagement with or into the path of said notched part. Inclined portions or ways lead to the notch so as to guide the rod into the notch and thus permit the lever to be locked when released by 90 the operator.

The contacting part 23, preferably in the form of a vertical shoe having curved ends, is carried by the forward end of the slide-bar 13, being thereby connected with or 100 forming part of the car mechanism C. This contacting part is adapted to coöperate with other contacting parts 24 at the several landings, for the purpose of coöordinating the car mechanism with the shaft gate locks. 105

The locking device installed in connection with the shaft gate at each landing is designated generally by the reference character L. The construction of and the specific manner of operating this device may 110

be varied. I have illustrated and prefer a very simple construction, wherein the lock 29 for the gate and the contacting part 24, are constituted in one movable element, 5 preferably a slide or plunger 29 operating in a guide recess in a suitable base plate, casing or support 45. As shown this slide operates transversely of the shaft gate, one end forming the contacting part 24 and the 10 other end being adapted to occupy a position behind the gate so as to lock the same closed. For purposes of adjustment the contact part 24 is preferably screwed to the body of the slide, a lock nut 26 being provided 15 to hold the adjustment.

The lock, and the therewith connected contacting part 24, are operated automatically upon the gate being completely closed. To this end a spring 27 and detent 28 are 20 provided. The spring urges the bolt of the lock toward locking position, and the detent automatically engages the bolt (or a connected part) when the bolt is withdrawn, and holds it and the contacting part 24 in 25 this condition against the tension of the spring. The object of the detent is to keep the controller inoperative and to prevent the bolt pressing against the door which would prevent the latter from moving freely. The 30 door when open, however, will act to keep the bolt and contacting member 23 in actuated position should the detent become disengaged. The gate in the last portion of its closing movement, after its rear edge has 35 passed the bolt, disengages the detent so that the bolt is free to shoot into locking position behind the gate, this same movement restoring the contacting part 24 to normal position. The construction and arrangement of the detent may, of course, be 40 varied. As shown it is slidable in a guide recess in the base plate transversely to the slide 29, which is provided with a recess 30 in its side positioned to be engaged by the 45 end of the detent when the lock is withdrawn. A spring, 31 presses against the detent to urge it into engagement with the slide, and a pin 32 projecting upward from the detent enables it to be released at the 50 proper moment by a pin 33 projecting from the door. A cover plate, which protects and holds the slide and detent in place, has been omitted from the drawings for clearness of illustration.

55 When the car is brought to a landing the contacting parts 23, 24 are opposite each other, though not necessarily in contact. The car mechanism and the shaft door lock are thus coördinated, and brought into co-operative relation, so that movement of one will cause movement of the other. The nature, location, and manner of connecting the operating means wherewith the operator withdraws the bolt of the door lock 60 and actuates the car mechanism may be

varied, but in the present embodiment of the invention such means is located at each landing, and, as shown, includes the slide rod 34 on the shaft door. This rod is pivotally connected at one end with an arm on 70 a vertical shaft 35 carried by the door adjacent its rear edge; and at the lower end of this shaft is an arm 36, which when the rod 34 is slid to the right presses forward against the upstanding portion 37 on the 75 slide 29, thus moving the latter against the tension of its spring so as to withdraw the locking portion 25, thereby permitting the gate to be opened by the operator continuing to push to the right on the rod 34. A 80 spring 49 is provided for restoring the slide rod 34, the shaft 35 and the arm 36 to normal positions with relation to the door.

It will thus be seen that in the particular embodiment of the invention illustrated, the 85 effort of the car operator is applied first to the shaft door lock to withdraw the same, and this effort is transmitted to the car mechanism through the thrust of the contacting member 24 against the contacting 90 member 23. As long as the door is open and until it is entirely closed and re-locked the parts remain in this condition, that is to say, with the door lock withdrawn and the controller in the car rendered inoperative. But, when the door has been entirely 95 closed, and the detent 28 has been thereby disengaged from the slide 29, the latter is restored to gate-locking position by means of its spring, and the car mechanism being 100 no longer held by the contacting member 24 is free to return to normal position. It will be obvious that the slide 29 in its return movement might be caused to positively restore the car mechanism, or that 105 the latter might be provided with a spring for the purpose, or the weight of the locking rod 19 may be relied upon to return the car-carried parts to the position shown in Fig. 1.

110 It will be observed that in the embodiment of the invention shown the operating means for releasing the shaft door lock and actuating the car mechanism is distinct from the controller lever, and, furthermore, it is 115 not necessary to bring the controller lever to neutral position in order to operate its locking mechanism. For this purpose a yielding connection is provided between the locking rod 19 and the car contacting member 23, and inclined portions or ways lead to the notch 22, so that if the rod is thrust upward into locking position when the controller is not in neutral mid-position, it can yield downward and then spring upward 120 into engagement with the notched part 22 when the controller is brought to neutral position. As shown in the drawings, the arm 20 is loose on the rock-shaft 17, though its movement relative to the latter is prefer- 125 130

ably limited by a pin and slot, as indicated at 40, and a spring 39 is arranged as a yielding resilient connection between the shaft and an arm.

- 5 It is to be noted that the operator can open the door only when his car is at the landing. The height of the contact member or shoe 23 determines a certain permissible range above or below the exact coincidence with the landing within which the door can be opened. Above and below these limits the contacting member 24 is barred by rigid guards 41, 42, carried by the car in vertical alinement with the shoe 23, so that 10 if an attempt is made to open the gate when the part 24, or a part of its operating mechanism, is opposite one of these guards the operator will find it impossible to move the slide rod 34 to the right so as to disengage the door lock.

While I have shown and described a suitable and preferred embodiment of my invention, I wish it to be understood that numerous changes and reversals may be made 20 without departing from its scope.

25 What I claim as new is:

1. In an elevator safety system, a horizontal rigid slide at the landing mounted for movement perpendicularly to the plane 30 of the landing door toward and from the elevator shaft, a spring for urging said slide into the path of the door to bar the same against opening, means on the door for moving said slide inwardly of the shaft 35 to release the door, an automatic detent at the landing for holding said slide in its inward position against the action of the spring, and means whereby the door in closing frees the slide from the detent.

40 2. In an elevator safety system, the combination of a rigid contact member movably mounted on the car for fore and aft movement transversely of the gap between the car and landing, a controller lock connected therewith, a horizontal spring-pressed slide adjacent the landing door also movable transversely to the gap, said slide being normally in locking relation to the door and having a contact portion to operate with the contact member on the car, and an automatic detent adapted to hold said slide in its unlocked position and to be disengaged by the door in closing.

45 3. The combination with a landing door, a handle thereon, a vertical rock-shaft on the door operated by said handle, a door-locking device near the bottom of the door, means on the lower portion of the rock-shaft for displacing said device from locking position, and a contacting portion connected with said device, of a coöperative contacting member on the car, a car controller, and means connected with the said car member for rendering said controller inoperative.

50 4. The combination with a landing door,

a horizontal slide rod thereon, a vertical rock-shaft connected with the end of the said slide rod, said rock-shaft mounted on the rear portion of the door, an arm on the lower end of the rock-shaft, a spring-urged 70 door-locking bolt on the landing in position to be acted upon by said arm, and a contacting portion connected with said bolt, of a coöperative contacting member on the car, a car controller, and means connected with the said car member for rendering said controller inoperative.

5 The combination with a landing door, a spring-urged part for locking said door, an automatic detent adapted to engage and 80 hold said part in its unlocked position free of the door, and means whereby the door disengages said detent in closing, of a car-controller, means on the car for rendering the controller inoperative, and coöperative 85 contacting portions on the car and at the landing to establish operative connection between the said means on the car and the door-locking means at the landing.

6. In an elevator lock, the combination of 90 an elevator shaft door, a lock for the same, means on the elevator car for breaking a circuit controlling the movement of the car, and mechanism including coöperative contacting portions connected respectively with 95 said lock and circuit-breaking means for co-ordinating these instrumentalities.

7. The combination with an elevator shaft door and a lock for the same, of a controller in the elevator car, a lock for said controller, 100 means on the car for breaking a circuit controlling the movement of the car, and means for connecting said controller lock and circuit-breaking means with said door lock when the car is at the landing.

8. In combination with an elevator shaft door and with an elevator car having a controller and suitable mechanism for rendering the same inoperative, of a slide at the landing having a portion for locking said 110 door and a portion coöperative with said mechanism on the car, and a detent for holding said slide when the latter is moved to unlock the door, and a spring for restoring the slide said detent being disengaged by the 115 closing of the door.

9. In combination with an elevator shaft door and with an elevator car having a controller and suitable mechanism for rendering the same inoperative, of a movable element 120 at the landing serving both as a lock for the said door and as a contacting part coöperative with the part of said mechanism on the car, a detent for holding said element when the latter is moved to unlock the door, a 125 spring for restoring said element, a projection whereby said detent is disengaged by the door in closing, and means carried by the shaft door for actuating said movable element.

10. The combination with a control lever in an elevator car and suitable mechanism thereon for rendering said lever inoperative, of a bolt for locking a landing door, a contacting part connected for movement with said bolt and adapted to coöperate with said mechanism on the car, a detent for holding said bolt and contacting part in shifted position, a spring for restoring them to normal position; said detent being disengaged by the closing of the door, and means carried by the shaft door for actuating said contacting part.
11. The combination with an elevator shaft door, and a movable contacting part at the landing, of parts on an elevator car comprising a controller, a lock for the same, a circuit-breaker, a contacting part coöperative with the contacting part at the landing, and a train of mechanism connecting the contacting part on the car with the said controller lock and with the circuit-breaker.
12. The combination with an elevator shaft door and a lock for the same, of a control lever in an elevator car, a lock for said lever, coöperative contacting parts connected with said door lock and lever lock, respectively, means independent of said lever for simultaneously withdrawing said door lock and actuating said lever lock, and a resilient connection between said lever lock and the therewith connected contacting part.
13. The combination with an elevator shaft door, a lock therefor, a contact part connected with said lock, and means on the door for unlocking said lock and moving said contacting part to operative position, of a controller on an elevator car, mechanism thereon adapted to be actuated by said contacting part to render said controller inoperative, and guard means on the car for preventing the movement of said contacting part and lock when the car is beyond a predetermined distance from the landing.
14. The combination with a landing door, a door lock having a contacting portion connected therewith, and means on the door for operating said lock and contacting portion, of a car having a controller, means for rendering the controller inoperative, a contacting member connected with said means to coöperate with the other contacting portion, and guard means on the car extending vertically from said contacting member to obstruct movement of said contacting portion if the contacting member on the car is out of range therewith.

In testimony whereof I have signed my name to this specification in the presence of two subscribing witnesses.

WILLIAM T. DUNFORD.
